UNITED STATES PATENT OFFICE

WILLIAM A. K. HARRIS, OF CINCINNATI, OHIO, ASSIGNOR, BY MESNE ASSIGNMENTS, TO CARTHAGE MILLS INCORPORATED, OF CINCINNATI, OHIO, A CORPORATION OF OHIO

BLOCK-PRINTING MACHINE

Application filed June 29, 1926. Serial No. 119,442.

My invention relates to electrical controls for block printing machines such as are used in the printing of designs on a continuous strip of paint surfaced flooring, or in other forms of printing where a closed design or pattern is formed in a series of repeats, requiring an interrupted operation of the printing elements, as applied to the continuous piece moving step by step with relation to them.

It is the object of my invention to provide an electrical control for the blocks of a printing machine of the type noted, which is readily controllable to shift from one length of repeat design to another, and which utilizes the simplest type of operation and mechanism.

There have been a number of machines for printing closed pattern devices, chiefly limited to machines for printing rug repeat designs on a continuous piece of linoleum or asphalt saturated felt. These devices, having been universally, so far as I am advised, mechanical in their timing and operation, have called for expensive installations, hard to keep in proper repair and difficult to adjust for different types of work.

By the use of a master rotary switch, timed to operate with the work feed devices of the press, and solenoids, or electro-magnets for tripping the several print block release devices, I obtain a completely adequate, readily changeable press block control, which can be installed on flat block printing machines with a minimum of expense.

Among other things, it is my object to serve in operations by applying an automatic latch to those blocks which are used for printing the ends of designs, and releasing this latch when the blocks are to print, where as, with regard to the blocks which are used to print oftener than they are held out, the latch falls open by gravity and is operated to engage the block operating device, so that the machine will trip the latch and release

the block, at any cycle of operation when the latch is not positively held in place during the tripping period.

In the printing of rugs, the end border design blocks, for example, will be held out more than they are held in, and the body design blocks will print every time if the blocks are not positively latched by the timing mechanism, ready to be released the next time the solenoid power is taken off from the latch, permitting it to fall to open position.

In printing a rug with blocks which are say three feet wide, by twelve feet long to print a nine by twelve foot rug, using end blocks which contain eighteen inch ends for two adjoining rug designs, there will be one impression of an end block for every three impressions of body blocks, and thus with the body to be printed fed step by step, each body block for the several colors will be lowered to print three successive times, and then held up one time, and the end blocks for each color will be held up three times, and printed once, so as to make impressions where the body blocks were not impressed upon the piece.

I attain my objects by that certain construction and arrangement of parts of which a specific example will be described, and the novelty inherent therein, or in equivalents thereof, will be stated in the appended claims.

In the drawings:—

Figure 1 is a side elevation of one of the print block operating mechanisms, used for the "body" printing.

Figure 2 is a like view of one of the block operating means for end border printing.

Figure 3 is a plan view of a rug design, marked into zones to indicate body and end printing.

Figure 4 is a side elevation without detail, illustrating one type of flat block printing machine.

Figure 5 is a detail of the switch mecha-

nisms for timing the operation, and a dia-
grammatic view of the solenoid devices.

Figure 6 is a diagram showing two ar-
rangements of contacts.

5 Figure 7 is a side elevation of one of the
contact disks.

Figure 8 is a front elevation of a contact
disk for an "end" block control.

Figure 9 is a perspective of a contact piece.

10 Figure 10 is a front elevation of a contact
disk for a "body" block control.

Referring first to the showing of a typical
machine to which my invention may be at-
tached. In Figure 4 I show a bed 1, over
15 which a sheet of material to be printed is
moved in a step by step manner. The print-
ing blocks 2 are carried in frames 3, and are
lifted and brought down against the work
by means of cams 4, having shoes 5, extend-
20 ing therefrom, which serve to pull the blocks
down against the work.

As shown in Figures 1 and 2, the blocks
are provided with depending arms 6, having
notched shoulders 7, into which the latches
25 engage, and anti-friction rollers 8 at the
ends of the arms, whereby engagement is
made with the cams.

The arrangement is such that at the high
point of the cams 4, the rollers are lifted high
30 enough to permit the latches to disengage,
and at the low points of the shoes, the blocks
are pressed against the work to accomplish a
printing.

The usual latch in machines of the type
35 noted, consists of a hooked arm 9, mounted on
a shaft or rod 10, to which is attached a
weight arm, whereby the latch is swung auto-
matically in or out of an engagement which
40 will hold up the block against downward
movement, and high enough for its roller to
be out of engagement with the projecting shoe
on the cam.

As shown for illustration in Figures 1 and
2, the latch weight arm tends to pull into en-
45 gagement, the latch for the end block, and to
hold out of engagement the latch for the body
block. If, however, the latch which swings
out of the way, is held in latching position
50 past the high point of the cam for the block
being latched, then until the next operation of
the press, the block will stay out of opera-
tion, even if the latch be released, because
the weight of the block will hold the latch in
55 place. Where the latch swings into place by
gravity or a spring, some means is required
to release it, in order for the block to follow
the cam downwardly in any instance.

In Figure 5 are shown two latches 9, held
on shafts 10. The shafts have brackets 12
60 thereon, in which are held the weight arms
11. The weight arms are provided with
weights 13, and are connected each by means
of a link 14, pivotally connected to the arms,
and also pivotally connected to the cores 15 of
65 the operating solenoids 16.

The timing switch device controls the pas-
sage of electric current to the solenoids, re-
sulting in swinging the latch to the left of
Figure 5, out of meshing position, as urged by
its weight arm, and swinging the latch to the
70 right in said figure to meshing position, from
which its weight arm urges it away. From
what has been stated, it will be evident that
the latch to the left is for use with the least
operated blocks or in this case end blocks,
75 and the latch to the right is for the most
operated or body block.

As shown in Figure 3, the end blocks may
be made to print the zones A of a design for a
rug, for example, serving in this instance for
80 two rugs, and body blocks will print the zones
B of the rug design. The instance noted of
a nine by twelve rug can be applied directly
to this outlined print design.

The timing devices are mounted in a frame
composed of standards 20, which journal a
shaft 21, on which the contact disks are
mounted. Segmental mounting plates 22 are
arranged on the standards at the two ends of
the shaft, to mount the contact brushes. In
85 the upper corners of the segmental mounting
plates are arranged two rods 23, and 24, and
the brushes are set over these rods. The
brushes have bodies 25, arranged to slide
over the rods, and to be clamped in set posi-
90 tion with set screws, and on the bodies are
conductive fingers 26, say of copper strip,
which engage the peripheries of the contact
disks. The contacts on one rod form the ter-
minals for one side of separate circuits to the
95 several solenoids, and the contacts on the
other rod serve as the other terminals. Thus,
when the brushes are bridged by conductive
strips on the peripheries of the contact disks,
circuits are closed to the solenoids of the
100 pairs of brushes bridged. As in any such
arrangement, one side of each circuit may be
to a ground connection.

The disks are formed of fibre bodies 27,
held between metal or fibre plates 28, which
105 plates are apertured to be arranged over the
shaft 21. The contacts proper are in the form
of plates 29 on the peripheries of the disks,
the plates being longer for the body block
controls than for the end block controls in
110 machines of the type illustrated, as suitable
for use with my invention. This feature is
arranged for use with the particular ma-
chine, and is not necessary in other types of
machines to provide this particular arrange-
115 ment.

On each disk, as the plate 29 terminates,
there is a step 30 in the periphery of the
disk, so that a quick break is provided for
the operation of the rotary switch, composed
120 of each disk, and its two wiping or contact
fingers.

The drive for the timing switch element
comes in the illustration from the shaft 31,
125 which is driven with the feed for the ma-

terial, and the block lowering and raising cams. This shaft has a gear 32, meshing with a gear 33, on shaft 34. On the shaft 34 is a gear 35. The gear 35 engages the gear 36 on the shaft of the timing switch.

5 The gear can also drive a companion set of switches as indicated in Figure 6, which may be set for a different speed of operation and a different timing. In this instance the gear 35^a is mounted on an arm 35^b and is planetary of the gear 35.

10 In the printing of shorter units, it is necessary to drive the timing switches more rapidly with relation to the feed of the material than with longer units, since the units to be printed are shorter, and a single complete revolution of the switch must cover a control for each printing cycle, and the switch must be back to starting position in 15 less time than when longer units and more impressions are to be made. Thus, when using one split end block, and one body block, the timing switch disk for the end block will have to revolve one full revolution for each 20 two steps of movement, whereas with three body blocks, and one end block, it will have to revolve once in every four printing periods.

25 This change is readily accomplished by means of gears to be changed on the time shaft, since the planetary gear can be swung into mesh with any sized gear on the said time shaft.

30 Having thus described a typical instance of use of my invention, what I claim as novel in the invention, and desire to secure by Letters Patent is:—

35 1. In a block printing machine having means for raising and lowering a series of printing blocks, latches to hold said print blocks out of operation, electrical devices to control the movement of said latches, and a master switch driven with the said printing machine, and connected to control the flow of current to said electrical devices, said master switch comprising a series of rotary contacts, said contacts constructed as disks on a shaft having in their peripheries conductive plates of less length than said peripheries, and conductive fingers arranged to engage said disks, 40 and arranged in pairs for each disk, whereby the conductive plates on the disks close a circuit between said fingers.

45 2. In a flat block printing machine, the combination of a series of print blocks, means for raising and lowering said blocks, latches for the blocks to hold them out of operation, means urging the latches of blocks which are to be printed infrequently to latching position, and means urging the latches of the 50 blocks which are to be printed frequently to unlatching position, and a master control element driven with the drive for the blocks, and connected to periodically unlatch the one set of latches, and periodically hold the other set 55 in latching position, said master control

element being constructed as a master electrical switch and electrical devices for acting upon the latches.

3. In a flat block printing machine, the combination of a series of print blocks, means for raising and lowering said blocks, latches for the blocks to hold them out of operation, means urging the latches of blocks which are to be printed infrequently to latching position, and means urging the latches of the 70 blocks which are to be printed frequently to unlatching position, and a master control element driven with the drive for the blocks, and connected to periodically unlatch the one set of latches, and periodically hold the other set 75 in latching position, said master control element being formed as a rotary switch, comprising a series of rotary contact members, and contact fingers engaging the same, one disk and contact finger assembly serving to 80 control the latching of each block.

4. In a flat block printing machine, the combination of a series of print blocks, means for raising and lowering said blocks, latches for the blocks to hold them out of operation, 90 means urging the latches of blocks which are to be printed infrequently to latching position, and means urging the latches of the blocks which are to be printed frequently to unlatching position, and a master control element driven with the drive for the blocks, and connected to periodically unlatch the one set 95 of latches, and periodically hold the other set in latching position, said master control element being formed as a rotary switch, comprising a series of rotary contact members, and contact fingers engaging the same, one disk and contact finger assembly serving to 100 control the latching of each block.

5. In a flat block printing machine, the combination of a series of print blocks, means 105 for raising and lowering said blocks, latches for the blocks to hold them out of operation, means urging the latches of blocks which are to be printed infrequently to latching position, and means urging the latches of the 110 blocks which are to be printed frequently to unlatching position, and a master control element driven with the drive for the blocks, and connected to periodically unlatch the one set of latches, and periodically hold the other set 115 in latching position, said master control element being formed as a rotary switch, comprising a series of rotary contact members, and contact fingers engaging the same, one disk and contact finger assembly serving to 120 control the latching of each block.

6. In a flat block printing machine, the combination of a series of print blocks, means for raising and lowering said blocks, latches for the blocks to hold them out of operation, means urging the latches of blocks which are to be printed infrequently to latching position, and means urging the latches of the 125 blocks which are to be printed frequently to unlatching position, and a master control element driven with the drive for the blocks, and connected to periodically unlatch the one set of latches, and periodically hold the other set 130 in latching position, said master control element being formed as a rotary switch, comprising a series of rotary contact members, and contact fingers engaging the same, one disk and contact finger assembly serving to 135 control the latching of each block.

open position, said master control element being formed as a rotary switch comprising a series of rotary contact members, and contact fingers engaging the same, one disk and contact finger assembly serving to control the latching of each block, and means for rotating said contact members as a unit, once for each complete cycle of printing successive closed end patterns, in which the infrequently moved blocks form the ends.
